[57] **CLAIM**

The ornamental design for a boot, as shown and de-
scribed.

DESCRIPTION

FIG. 1 is a perspective view of a first embodiment of a
boot showing my ornamental design;

FIG. 2 is a left side elevation view of the first embodi-
ment thereof;

FIG. 3 is a right side elevation view of the first embodi-
ment thereof;

FIG. 4 is a front elevation view of the first embodiment
thereof;

FIG. 5 is a rear elevation view of the first embodiment
thereof;

FIG. 6 is a top plan view of the first embodiment
thereof;

FIG. 7 is a bottom plan view of the first embodiment
thereof;

FIG. 8 is a perspective view of a second embodiment of
a boot showing my ornamental design;

FIG. 9 is a left side elevation view of the second em-
bodiment thereof;

FIG. 10 is a right side elevation view of the second
embodiment thereof;

FIG. 11 is a front elevation view of the second embodi-
ment thereof;

FIG. 12 is a rear elevation view of the second embodi-
ment thereof;

FIG. 13 is a top plan view of the second embodiment
thereof;

FIG. 14 is a bottom plan view of the second embodi-
ment thereof;

FIG. 15 is a perspective view of a third embodiment of
a boot showing my ornamental design;

FIG. 16 is a left side elevation view of the third embodi-
ment thereof;

FIG. 17 is a right side elevation view of the third em-
bodiment thereof;

FIG. 18 is a front elevation view of the third embodi-
ment thereof;

FIG. 19 is a rear elevation view of the third embodi-
ment thereof;

FIG. 20 is a top plan view of the third embodiment
thereof;

FIG. 21 is a bottom plan view of the third embodiment
thereof;

FIG. 22 is a left side elevation view of a fourth embodi-
ment of a boot showing my new design; and,

FIG. 23 is a left side elevation view of a fifth embodi-
ment of a boot showing my new design.

The other views of the fourth and fifth embodiments are
identical to FIGS. 3-7.
